(57) **CLAIM**

The ornamental design for a seat cover dispenser, substantially as shown and described.

DESCRIPTION

FIG. 1 is a front, raised perspective view of a seat cover dispenser according to the invention;

FIG. 2 is a front view of the seat cover dispenser of FIG. 1;

FIG. 3 is a rear view of the seat cover dispenser of FIG. 1;

FIG. 4 is a right side view of the seat cover dispenser of FIG. 1;

FIG. 5 is a left side view of the seat cover dispenser of FIG. 1; and,

FIG. 6 is a top view of the seat cover dispenser of FIG. 1. The broken-lines show portions of the seat cover dispenser that form no part of the claimed design. The dash dot lines immediately adjacent to the claimed areas in the views represent the boundaries of the claimed design. None of the broken lines form any part of the claimed design. The seat cover dispenser is shown with symbolic breaks in its width. The appearance of any portion of the seat cover dispenser between the break lines forms no part of the claimed design.
